US00D853173S

(12) **United States Design Patent** (10) **Patent No.:** **US D853,173 S**
(45) **Date of Patent:** **** Jul. 9, 2019**

(54) **SLOW COOKER KITCHEN APPLIANCE**

(71) Applicant: **Columbia Insurance Company**,
Omaha, NE (US)

(72) Inventors: **William A. Bucklew**, Wilmette, IL
(US); **Michael R. Mastroianni**, Crystal
Lake, IL (US); **Bikram Sohi**, Buffalo
Grove, IL (US)

(**) Term: **15 Years**

(21) Appl. No.: **29/592,662**

(22) Filed: **Feb. 1, 2017**

(51) LOC (11) Cl. **07-02**
(52) U.S. Cl.
USPC **D7/357**

CLAIM

The ornamental design for a slow cooker kitchen appliance, as shown and described.

DESCRIPTION

FIG. 1 is a top perspective view showing our new design for a slow cooker kitchen appliance;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown illustrate portions of the slow cooker kitchen appliance that form no part of the claimed design.

1 Claim, 6 Drawing Sheets
